2,646,494

UNIT FOR CUTTING MATERIALS BY HEAT

Robert W. Fegan, Kenmore, N. Y., assignor to
 George B. Hart, Inc., Rochester, N. Y., a corporation of New York

Application June 21, 1950, Serial No. 169,499

1 Claim. (Cl. 219—29)

1
 My invention relates to a unit for cutting materials by heat, particularly such materials as polystyrene products, thermoplastics and other materials which may be readily cut upon being contacted by a high temperature resistance wire.

An object of my invention is to provide a cutting unit particularly suitable for cutting styrene products, thermoplastics and other materials by a current carrying high resistance wire which is inexpensive to manufacture and convenient to use.

A further object of my invention is to provide a resistance wire so mounted with relation to a work surface that polystyrene products, thermoplastics and other materials may be conveniently cut for the purpose of making decorative designs for use in displays by florists, in funeral work, in trimming store windows and for other decorative purposes.

My invention further contemplates a high resistance wire adapted easily and conveniently to cut polystyrene products, thermoplastics and other materials when heated by an electric current, the wire being so arranged with respect to a platform to one end of which the resistance wire is anchored and with respect to a mounting member to which the other end of the resistance wire is anchored that when the wire expands or lengthens due to heat the increased length is automatically taken up so as to maintain the wire taut and facilitate the cutting operation.

Other objects and advantages of my invention will be particularly set forth in the claim and will be apparent from the following description, when taken in connection with the accompanying drawings, in which:

Fig. 1 is a perspective view of the cutting unit of my invention;

Fig. 2 is a sectional view taken substantially on the line 2—2 of Fig. 1 in the direction indicated by the arrows;

Fig. 3 is a view of the under side of the box or platform which houses parts of the unit; and

Fig. 4 is a sectional view taken substantially on the line 4—4 of Fig. 3 in the direction indicated by the arrows.

It has been customary practice in decorative work such as might be used by florists or funeral directors or in the trimming of store windows to make cut-outs of polystyrene products, thermoplastics and other materials for the purpose of producing decorative designs. For example, in the trimming of store windows, it is sometimes desirable to make cut-out designs for use in connection with snow scenes. Such cut-

out designs, for example, block letters, may be made of polystyrene or other materials and such decorative designs have many other uses in floral and funeral work.

Heretofore it has been the practice to cut such polystyrene products, thermoplastics or other materials with a metal saw which is difficult to handle, does not produce a smooth cut and is difficult to maintain and control along a desired line of cut. I have found that such materials may be more easily cut and a smooth cut appearance produced when the cut is made by a current carrying high resistance wire.

The cutting unit of my invention may comprise a box or rectangular shaped structure, generally indicated by the numeral 11, which has a work receiving platform or top surface 12 and side and end walls 13. Referring now to Fig. 3 which is a view of the under side of the box 11, as indicated at 14, the unit is connected by a suitable electric cord to a wall socket in the usual manner. A lead 16 from the source of current passes to a transformer, diagrammatically illustrated at 18, adapted to step down the current from, let us say, 110 volts to 9½ volts. From the transformer 18, the current flows through a wire 19 to a terminal 21.

As shown most clearly in Fig. 4, the terminal 21 includes a threaded conducting element 22 which extends through an aperture formed in a bracket 23 secured in any suitable manner beneath the top wall of the box 11. Suitable nuts 24 are provided for holding the lead 19 in place and the threaded member 22 is insulated from the bracket 23 by means of insulation members 25. A conducting washer 27 is carried by the threaded member 22 and a resistance wire 28 is wound around the threaded member 22 and clamped in position by a thumb nut 29.

The resistance wire 28 may be a nickel chrome alloy which is highly resistant to current flow therethrough and does not readily oxidize. The other end of the resistance wire 28 is connected as shown most clearly in Fig. 2 to a conducting threaded member 31 which is mounted in an aperture formed in a cap 32. The resistance wire 28 may be wound around the threaded member 31 and clamped between a washer 33 and a thumb nut 34. The parts may be held in position by a nut 35 threaded on the inner end of the threaded member 31. The cap 32 extends over the end of a gooseneck shaped member 36 which is a conductor.

As shown most clearly in Fig. 3, the gooseneck shaped conducting member 36 extends

through an opening formed in the platform 12 and is rigidly secured by welding 37 to a support 38. Preferably the box 11 is a conductor and is connected as shown at 39 to a wire 41 which connects with the transformer as shown at 42. A switch 43 is connected in the circuit so that upon opening and closing the same, current may flow as above described through the resistance wire 28. The box of the cutting unit may be grounded as indicated at 45.

One fact of importance should be particularly noted. The resistance wire 28 tends to expand or lengthen when heated. The amount of expansion may be as much as $\frac{3}{8}$ " in a 12" length of wire. In order to obtain efficient cutting, the wire should be maintained taut; otherwise it is difficult to obtain a clean or sharply defined cutting of the material. This is accomplished in my invention by anchoring the wire at the terminal 21 and maintaining the gooseneck 36 slightly under tension. That is, the wire 28 is anchored at its lower end and its upper end is tied to the end of the gooseneck in such manner as to place the wire under tension. The gooseneck 36 thus has a slight resiliency tending to cause its outer end or its point of attachment to the resistance wire 28 to move away from the platform and thus automatically take up for any expansion in the resistance wire as it is heated.

I have found the cutting unit above described extremely useful in cutting such materials as polystyrene products, thermoplastics and other materials which may be cut by heat. The product to be cut to form, for example, block letters or other designs, may easily be moved over the platform with relation to the cutting wire and accurate control of the design to be cut can be obtained by a reasonably skillful worker.

While I have shown and described the preferred form of my invention, it will be appreciated that various changes and modifications may

be made, particularly in the form and relation of parts, without departing from the spirit of my invention as set forth in the appended claim.

I claim:

- 5 Apparatus for cutting materials comprising, in combination, a grounded box-like frame having a planar top surface upon which the materials to be cut are placed, said top surface having an opening toward the front thereof, 10 a gooseneck shaped conducting member carried by and in conducting relation with the platform adjacent the rear thereof and extending forwardly to a position with its free end above the opening, a high resistance conducting wire 15 connected to the end of said member, a terminal insulated from the frame below the top surface thereof, said resistance wire extending downward through said opening and being connected to said terminal, said top surface affording a 20 planar area over which the articles to be cut may be moved in cutting relation to said wire which planar area is normal to said wire and unobstructed except for the lower end of said gooseneck, and means including a switch and 25 a transformer located below said planar surface for completing the circuit through the resistance wire, said gooseneck shaped member being sufficiently resilient that the end of the member to which the wire is attached tends to move away 30 from the terminal beneath the top surface to maintain the wire taut when it lengthens due to heat.

ROBERT W. FEGAN.
